REGENERATIVE FILTER

Ludwig W. Blau and James S. Watt, Houston, Tex., assignors to Standard Oil Development Company, a corporation of Delaware

Application June 22, 1934, Serial No. 731,946

10 Claims. (Cl. 178—44)

This invention relates to an improvement in filters.

It has been known how to combine electric networks so as to render them frequency selective.

5 Thus it is possible to make low pass filters which pass low frequencies and discriminate against high frequencies. High pass filters, on the other hand, pass high frequencies and discriminate against the low frequencies. Such a filter is the 10 subject of the copending application of Ludwig W. Blau, U. S. Serial No. 659,822, entitled "Method and apparatus for eliminating low frequencies", filed May 6, 1933.

When filters are to be included in electrical 15 recording systems where high accuracy is required, it becomes necessary to damp out all oscillations originating in the filter itself. This is done successfully in the filter which is the subject of the above mentioned patent application. However, the introduction of damping renders the 20 cut-off of the filter less sharp so that more stages must be added to make up for it. This means that the filter becomes larger and more expensive to construct. The invention which is the subject 25 of this application permits of building a damped filter of a few stages with a sharp cut-off heretofore obtained only by using many more stages.

The invention will be fully understood from the following description taken in connection with 30 the accompanying drawing in which latter—

Fig. 1 is a generalized schematic illustrating one form of the invention;

Fig. 2 is a generalized schematic illustrating a modified form of the invention;

35 Fig. 3 is a diagrammatic representation of a specific form of circuit embodying the invention, and

Fig. 4 is a diagrammatic representation of an 40 arrangement of apparatus for reflection shooting.

Referring particularly to Fig. 1 of the drawing reference numeral 1 designates an input impedance and numeral 2 designates an output impedance. An electric circuit connects the impedances. The input impedance 1 is connected to an oscillator 3 or other source of alternating current. A plurality of parallel branches 5, 6 and 7 are provided in the electric circuit. Each branch includes an impedance 10. An impedance 12 is provided in the circuit between the impedance 1 and the branch 5. An impedance 13 is provided in the electric circuit between the branch 7 and the impedance 2. Impedances 14 are provided in the circuit between adjoining branches. The impedances 1, 2, 10, 12, 13 and 14

may be resistors, inductance coils, condensers, or combinations in series or in parallel of resistors, and/or inductance coils and/or condensers. The particular impedance used depends upon the kind of filter it is desired to build.

An amplifier is operatively connected across the input and output impedances 1 and 2. The amplifier comprises a vacuum tube 16. The vacuum tube includes a grid 17 and filament 18 which are connected across the output impedance 2. A 10 plate 20 of the vacuum tube is with the filament 18 connected across the input impedance 1 of the filter. A, B, C and other battery connections are not shown because their insertion into a circuit such as described here is familiar to those 15 skilled in the art. The vacuum tube 16 while illustrated as a three electrode tube may be any four electrode or multiple electrode tube.

The circuit operates as follows: The oscillator 3 impresses a voltage across the input impedance 20 1 which is transmitted through the filter to the output impedance 2. The frequency content is 25 changed by the filter, some of the frequencies being passed while others are discriminated against. Thus if it is assumed for a moment that a high pass filter is being used with a cut off at 40 cycles, the frequencies higher than 40 will pass through the filter with little or no attenuation, while the lower frequencies are attenuated. Thus the filter may pass all 50 cycle 30 energy, 95% of the 40 cycle, 75% of the 30 cycle, 35% of 20 cycle and 5% of 10 cycle energy. The addition of more stages would make the cut off sharper; thus by using twice as many stages one would obtain the following percentages at the 35 different frequencies:

Cycle energy	Passed by filter
50	100
40	90
30	56
20	12
10	0.25

Table I

In the last mentioned filter the cut off would be much sharper, but the addition of the stages would be costly and the filter would be larger.

According to the invention, the voltage across 50 impedance 2 is impressed upon the grid of the vacuum tube 16 where it is amplified and is in turn impressed upon the input impedance 1. From the input impedance 1 the amplified voltage is transmitted again to the impedance 2. It is then reimpressed upon the grid of the vac- 55

uum tube which again amplifies it and impresses the amplified voltage again upon the input impedance. The operation proceeds thus until a large number of round trips have been made. On 5 each round trip the filter discriminates against all frequencies in the attenuation band so that the energy content of these frequencies is reduced each time.

Thus if we assume that say a fraction p of a 10 certain frequency impressed upon the input impedance 1 is transmitted to the output impedance 2 and reimpressed upon the input, then on the first trip the voltage of this frequency impressed 15 on impedance 1 is 1; on the second trip p , on the third trip p^2 , on the fourth trip p^3 , and on the n -th p^{n-1} . Then after $n+1$ round trips, we have for the sum of all these fractions

$$S = 1 + p + p^2 + p^3 + p^4 + \dots + p^n$$

$$= 1 + p(1 + p + p^2 + p^3 + \dots + p^{n-1})$$

$$= 1 + pS - p^n$$

whence

$$25 \quad S = \frac{1 - p^n}{1 - p}$$

Now since p is less than unity, p^n approaches zero as a limit and for a large number of round trips we can write

$$30 \quad S = \frac{1}{1 - p}$$

The sum S gives the amplification, due to regeneration, of the frequency of which the filter passes a fraction p of the input voltage. But, in 35 the example assumed above, we had the following values of p for the different frequencies:

10 *Table II*

Freq.	p
50	1
40	.95
30	.75
20	.35
10	0.05

15 Substituting these values of p in the equation for S above, we have the table for the amplification of the different frequencies:

10 *Table III*

Freq.	S
50	Infinity, say 1000
40	20
30	4
20	1.53
10	1.05

Since an infinite amplification is impossible one would set the regeneration possible at 50 cycles to a slightly smaller value than unity; assuming 0.999 and higher values can be used in practice, the amplification at 50 cycles would be 1000 times. Recalling now the values given in Table II which give the characteristics of the filter without regeneration, we find that whereas without regeneration a frequency of 30 cycles was 35% as strong as 50 cycles, the regenerative filter has reduced it to 0.4%. The cut off has been made as sharp as would be obtained with a filter with more than 10 times as many sections. It is not 0 proposed to limit the invention to a three section filter such as has been shown in Fig. 1.

If the filter used is of the high pass type with a cut off frequency at say 40 cycles, then the voltage resulting across the output impedance 2 due 5 to the impression of a frequency of 5 cycles across

the input impedance 1 will be very small or even negligible on account of the filter action of the filter. This low voltage across the output impedance 2 is, however, impressed across the grid and filament of the vacuum tube 16 and for this frequency of five cycles, or for any other frequency below the cut off frequency of the filter, the grid and filament of the vacuum tube will therefore be practically shorted so that there will be no amplification in the plate current 10 due to this low frequency. The voltage resulting across the output impedance 2 due to a high frequency impressed across the input impedance 1 may be very large. Any such voltage impressed upon the grid and filament of the vacuum tube 15 16 will result in an amplification by the vacuum tube 16 of the voltage across the output impedance 2 by a factor which depends upon the construction of and the particular voltages impressed upon the vacuum tube 16. It is evident therefore 20 that all frequencies higher than the cut off frequency will have their amplitudes magnified by a predetermined factor depending upon the type of vacuum tube selected. In the case of a low pass filter the reverse would be true, the low frequencies would be amplified while the high frequencies which the filter attenuates suffer deleterious discriminations. In the case of band pass filters, the frequencies lying in the pass band would be amplified while those lying in the 25 attenuation band would be reduced in amplitude. While the source of alternating current has been described as an oscillator 3, it will be understood that any other electrical input such as a broadcasting microphone, a phonograph pick-up or 30 any other electrical input can be substituted for the oscillator 1 and some of the advantages of the invention will be retained.

Referring particularly to Fig. 2, a modified form of the invention is shown in which the filter is 40 identical with the filter illustrated in Fig. 1 and like reference numerals are used to designate like parts. In this figure, however, the grid 17 and filament 18 of the vacuum tube 16 are connected across the impedance 10 of the shunt arm 7. The plates 20 and filament 18 are connected across the impedance 10 of the shunt arm 5. Alternatively the grid and filament of the vacuum tube can be connected across either the output impedance or any one of the later shunt arm impedances, and the plate 20 can be connected across the input impedance or any one of the earlier impedances and some of the advantages of the invention will be retained.

Referring to Fig. 3, the invention is illustrated 55 as applied to one of the filters which constitutes the subject matter of the copending application above referred to. In this figure reference numeral 25 designates an input resistance, such as the resistance of an electrical seismograph, and 60 numeral 26 represents an output resistance. An electric circuit connects the resistances. A plurality of parallel branches 27, 28, 29, 30 and 31 are provided in the circuit. Each branch includes a condenser 33 together with an inductance 34 and resistance 35 of a choke coil. A condenser 37 is provided in the circuit between the resistances 25 and the branch 27, and a condenser 38 is provided in the circuit between the branch 31 and the output resistance 26. A damping resistance 40 and a condenser 41 are connected in series in the circuit between each of the adjoining branches 27, 28, 29, 30 and 31. In the embodiment illustrated, the vacuum tube 16, identical in all respects with the vacuum tubes pre- 70

viously described, is connected through its grid and filament 18 across the output resistance 26. The plate 18 of the vacuum tube is connected with the filament across the branch 27.

- 5 Referring to the embodiment illustrated in Fig. 4, a preferred arrangement of apparatus for reflection shooting is shown in which reference numeral 43 designates the coil of a magneto-electrical seismograph such as is described in the 10 copending application Serial No. 626,132 of Ludwig W. Blau et al., entitled "Seismograph", filed July 29, 1932. The coil 43 is connected across the grid and filament of a vacuum tube 44 which may be a three-electrode or screen grid tube. The 15 vacuum tube 44 is connected to the input resistance 25 of the circuit previously described in connection with Fig. 3. The output resistance 26 of the circuit is connected to a vacuum tube amplifier 45 which in turn is connected to an oscillograph 46 which records the seismogram. The 20 vacuum tube 16 is connected through its grid and filament across the output resistance 26. The plate of the vacuum tube is connected with the filament across the input resistance 25. The vacuum 25 tube 44 if used is either of the same type as the vacuum tube 16 or if different tubes are used, the two types must require the same B voltages because of the fact that both tubes are supplied from the same source of B voltage. The 30 vacuum tube 44 is used where the input currents resulting from the inductance coil, or any other electrical input which may be inserted in its place, are very feeble and it is deemed desirable to amplify these feeble oscillations prior to their 35 impression upon the filter.

By the construction described, undesired frequencies are not amplified while desired frequencies lying in the pass band of the filter are amplified. A relatively sharp cut-off is obtained 40 as compared with that obtained with the previously known filters having the same number of sections. Alternatively, the same cut-off can be obtained as formerly by using a smaller number of sections.

45 Various changes may be made within the scope of the appended claims in which it is desired to claim all novelty inherent in the invention as broadly as the prior art permits.

We claim:

- 50 1. A selective amplifier, comprising an electric circuit constituting a filter with parts of the filter aperiodically damped for the natural frequencies of the filter and including impedances shunted across the circuit, and amplifying means one end 55 of which is connected across an impedance near the output end of the circuit and the other end of which is connected across an impedance relatively near the input end of the circuit so as to permit the passage and amplification of energy 60 from adjacent the output end to adjacent the input end for further filtering.

2. A selective amplifier, comprising an electric circuit constituting a filter with parts of the filter aperiodically damped for the natural frequencies 65 of the filter and including impedances shunted across the circuit, and a vacuum tube including a grid and filament connected across an impedance near the output end of the circuit and including a plate which with the filament is connected across an impedance relatively near the input end of the circuit so as to permit the passage and amplification of energy from adjacent the output end to adjacent the input end for further filtering.

- 75 3. A selective amplifier, comprising an electric

circuit constituting a filter with parts of the filter aperiodically damped for the natural frequencies of the filter and including impedances shunted across the circuit, and amplifying means one end of which is connected across the impedance at the output end of the circuit and the other end of which is connected across the impedance at the input end of the circuit so as to permit the passage and amplification of energy from the output end to the input end for further filtering. 10

4. A selective amplifier, comprising an electric circuit constituting a filter with parts of the filter aperiodically damped for the natural frequencies of the filter and including impedances shunted across the circuit, and a vacuum tube including a grid and filament connected across the impedance at the output end of the circuit and including a plate which with the filament is connected across the impedance at the input end of the circuit so as to permit the passage and amplification of energy from the output end to the input end for further filtering. 15

5. A selective amplifier, comprising an input impedance, an output impedance, an electric circuit constituting a filter connecting the impedances with parts of the filter aperiodically damped for the natural frequencies of the filter and including impedances shunted across the circuit, and amplifying means one end of which is connected across an impedance near the output 25 end of the circuit and the other end of which is connected across an impedance relatively near the input end of the circuit so as to permit the passage and amplification of energy from adjacent the output end to adjacent the input end for 30 further filtering.

6. A selective amplifier, comprising an input impedance, an output impedance, an electric circuit constituting a filter connecting the impedances with parts of the filter aperiodically 40 damped for the natural frequencies of the filter and including impedances shunted across the circuit, and a vacuum tube including a grid and filament connected across an impedance near the output end of the circuit and including a 45 plate which with the filament is connected across an impedance relatively near the input end of the circuit so as to permit the passage and amplification of energy from adjacent the output end to adjacent the input end for further filtering. 50

7. A selective amplifier, comprising the inductance coil of a seismograph connected across the grid and filament of a vacuum tube, an input impedance connected to the plate resistor of the vacuum tube, an output impedance, a filter connecting the impedances with parts of the filter aperiodically damped for the natural frequencies of the filter, impedances shunted across the circuit of the filter, amplifying means one end of which is connected across an impedance near the 60 output end of the circuit and the other end of which is connected across an impedance relatively near the input end of the circuit so as to permit the passage and amplification of energy from the output end to the input end for further 65 filtering, an amplifier connected across the output impedance, and an oscillograph connected to the amplifier.

8. A selective amplifier, comprising the inductance coil of a seismograph connected across the grid and filament of a vacuum tube, an input impedance connected to the plate resistor of the vacuum tube, an output impedance, a filter connecting the impedances with parts of the filter aperiodically damped for the natural frequen- 70

75

cies of the filter, the impedances shunted across the circuit of the filter, a vacuum tube including a grid and filament connected across an impedance near the output end of the circuit and 5 including a plate which with the filament is connected across an impedance relatively near the input end of the circuit so as to permit the passage and amplification of energy from the output end to the input end for further filtering, an amplifier connected across the output impedance, and an oscillograph connected to the amplifier.

9. A selective amplifier, comprising an electric circuit, constituting a filter with parts of the filter aperiodically damped for the natural frequencies 10 of the filter and including impedances shunted across the circuit, and amplifying means one end of which is connected across one of the impedances and the other end of which is connected across an impedance relatively near the

input end of the circuit so as to permit the passage and amplification of energy in the reverse direction to its passage through the filter for further filtering.

10. A selective amplifier, comprising an electric circuit constituting a filter with parts of the filter aperiodically damped for the natural frequencies of the filter and including impedances shunted across the circuit, and a vacuum tube including a grid and filament connected across an impedance and including a plate which with the filament is connected across an impedance relatively near the input end of the circuit so as to permit the passage and amplification of energy in the reverse direction to its passage through the filter for further filtering.
